UNITED STATES PATENT OFFICE.

MAURICE RENÉ JOHN BRUINE, OF NEW YORK, N. Y., ASSIGNOR TO FAUROT-SCOPE CORPORATION, A CORPORATION OF DELAWARE.

DESIGN FOR A MOTOR-VEHICLE SIGNAL.

Application filed October 28, 1921. Serial No. 511,151. Term of patent 14 years.

To all whom it may concern:

Be it known that I, MAURICE RENÉ JOHN BRUINE, a citizen of the United States, residing in the city of New York, in the county of New York and State of New York, have invented a new, original, and ornamental Design for a Motor-Vehicle Signal, of which the following is a specification, reference

being made to the accompanying drawing, forming a part thereof, in which the figure is a side elevation of a motor-vehicle signal showing my design.

I claim:

The ornamental design for a motor vehicle signal as shown.

MAURICE RENÉ JOHN BRUINE.
